UNITED STATES PATENT OFFICE.

JAMES GEORGE JACKSON, OF GLASGOW, SCOTLAND, ASSIGNOR TO J. G. JACKSON, LIMITED, OF GLASGOW, SCOTLAND.

EXTRUSION APPARATUS.

1,368,934.

Specification of Letters Patent. Patented Feb. 15, 1921.

Application filed June 16, 1920. Serial No. 389,382.

To all whom it may concern:

Be it known that I, JAMES GEORGE JACKSON, a subject of the King of Great Britain and Ireland, of Coustonholm Works, Pollokshaws, Glasgow, Scotland, have invented new and useful Improvements in or Connected with Extrusion Apparatus, of which the following is a specification.

This invention refers to extrusion apparatus for delivering charges of powdered, granular, plastic and like materials or substances, hereinafter referred to generally as material, of the type in which the material to be dealt with is delivered in charges each of equal or approximately equal quantity intermittently through a delivery tube by the operation of a helix mounted to rotate axially therein.

The improvements according to this invention comprise imparting automatically to the helix, or to each helix if more than one delivery tube is provided, a cycle of motions successively, as follows:—forward rotation, backward rotation, and period of rest. The invention also comprises improvements appertaining to construction and arrangement.

In the operation of apparatus according to this invention, forward rotation of the helix is utilized to produce extrusion, backward rotation to check extrusion which operates to assist in breaking the connection between the portion of the material constituting the charge to be delivered from the material of the supply, and in the period of rest produced the charge extruded may be removed and provision made for receiving the next charge to be extruded, say, into a formed receptacle.

An example of apparatus, provided with four horizontal delivery tubes, embodying improvements according to this invention will now be described with reference to the accompanying drawings, in which:—

Figure 1 is an end view partly in section, Fig. 2 is a side view with the lower portion omitted partly in section with portions of the mechanism removed, Fig. 3 is a side view on a reduced scale of the lower portion omitted in Fig. 2, and Fig. 4 is a plan view partly in section with portions of the mechanism removed, the section taken being about the line X X of Fig. 1.

The apparatus illustrated comprises a supply chamber A for holding a supply of

the material to be dealt with, provided with a hopper head for convenience in charging. From the base of the supply chamber A four delivery tubes B extend horizontally. Each delivery tube is furnished with a helix 60 B¹ adapted to extend from or near the discharge end of the delivery tube B across the base within the chamber A. C designates a driving shaft arranged with its axis horizontal and at right angles to the axes 65 of the delivery tubes B. Above the driving shaft C a cam disk D is mounted with its axis parallel to the driving shaft C. The disk D comprises a toothed wheel D¹ which gears with a pinion C¹. The pinion C¹ is 70 fixed on the driving shaft C by which it is driven. Upon one face of the disk D cams E, E¹, E² are provided situated about a path concentric to the axis and near the periphery of the disk. The cams, see Fig. 2, which 75 extend clockwise E from 1 to 2, E¹ from 2 to 3, and E² from 3 to 1 operate respectively, as will be hereinafter explained, to bring into action driving gear to produce:—E, extrusion; E², check extrusion; E¹, 80 period of rest. In this case the cam E is composed of two parts of which the part terminating at 2 is fixed to the disk and the other part which extends from 1 is mounted capable of limited adjustment circularly 85 about the center of the disk D. By this arrangement the distance between 1 and 2 may be altered to regulate the period of extrusion, and adjustment in this manner would also affect the period of check. The cam 90 E¹ from 2 to 3 is not adjustable. F, F¹ designate two toothed bevels mounted to rotate freely upon the driving shaft C arranged in gear on opposite sides with a driven wheel G. The gear wheels F, F¹ are 95 provided each with a clutch face adapted to be engaged by the faces of a clutch H located between them. The clutch H is mounted to slide axially upon and is connected to rotate with the driving shaft C and by axial movement be brought into driving connection with either of the two gear wheels F, F¹ or held in an intermediate position out of engagement from both. J designates a rocking arm, mounted about a horizontal pivot 100 J¹, the axis of the pivot being at right angles to the axis of the driving shaft C. The arm J is provided at its upper end with a lateral extension J² which is maintained in bearing contact with the cams E, E², E¹, as the 110

disk D rotates, by means of a spring K in tension. The lower end of the arm J engages with the clutch H and is arranged when rocked to move the clutch H axially 5 to and fro. The drive imparted to the driven wheel G may be transmitted to each helix by gearing, for instance, as indicated, consisting of a bevel gear G¹ fixed to rotate with the gear wheel G, a transmission shaft 10 L, to which is fixed a bevel gear P in mesh with the gear G¹, and four bevel gears P¹ in mesh respectively with four bevel gears R fixed respectively to the spindles of the four helixes B¹.

15 Receptacles S to be filled may be carried by a conveyer, a traveling band T for instance, to which intermittent progression may be imparted by any suitable means to bring successive receptacles S into position.

20 Within the supply chamber A a stirrer may be provided having, say, one or more radial arms N mounted upon a shaft D² fixed to rotate with the cam disk D, each arm having a blade N¹ extending across the supply chamber A and adapted to sweep in a circular path. The end of the supply chamber A through which the shaft D² extends may be formed in an integral part with the side walls and the radial arm or arms N may 25 be arranged close thereto, the opposite end may be open and be fitted with a door A¹. The door A¹ may be mounted to turn about a vertical axis at one side.

30 In the process of operation a constant drive is imparted to the shaft C in a counter-clockwise direction thereby rotating the cam disk D clockwise and the clutch H counter-clockwise. As rotation takes place the cams E, E², E¹ on the disk D engage successively

35 with the extension J² and acting in conjunction with the spring K cause the arm J to rock about the pivot J¹. Thus, when the cam E, portion 2, 1, is in operation the clutch H is held in driving connection with the gear 40 wheel F, and the drive is applied to the wheel G from whence it is transmitted to the helixes B¹ to produce extrusion. When the cam E², portion 1, 3, is in operation the clutch H is brought into driving connection 45 with the gear wheel F¹ whereby extrusion is checked, and when the cam E¹, portion 3, 2, is in operation the period of rest is produced, the parts then assuming the positions indicated at Fig. 1.

50 55 I claim:—

1. Extrusion apparatus comprising, a supply chamber, a delivery tube projecting from the supply chamber, a helix mounted axially within the delivery tube extending

from the supply chamber, and means controlled by the apparatus for imparting to the helix a cycle of motions, successively, consisting of forward rotation, backward rotation, period of rest, for the purposes set forth. 60

2. Extrusion apparatus comprising, a supply chamber, a delivery tube projecting from the supply chamber, a helix mounted axially within the delivery tube extending from the supply chamber, gearing for automatically 70 operating the helix comprising a driven element connected to rotate with the helix, two driving elements each in driving connection with the driven element, one a forward rotation driving element the other a backward 75 rotation driving element, and controlling gear for applying the drive successively first from the forward rotation driving element, secondly from the backward rotation driving element, and finally removed from both, 80 for the purposes set forth.

3. Extrusion apparatus comprising, a supply chamber, a delivery tube projecting from the supply chamber, a helix mounted axially within the delivery tube extending from the supply chamber, gearing for automatically 85 operating the helix comprising a driven bevel gear, two toothed driving bevels in gear on opposite sides with the driven bevel gear wheel, a driving shaft about which 90 the driving bevels are mounted to rotate, a clutch located between the driving bevels mounted to slide axially on the shaft, a cam disk rotated from the driving shaft, a rocking lever maintained at one end in bearing 95 contact with the cams and at the other connected to the clutch, for the purposes set forth.

4. Extrusion apparatus comprising, a supply chamber, a delivery tube projecting from the supply chamber, a helix mounted axially within the delivery tube extending from the supply chamber, a horizontal driving shaft arranged at right angles to the axis of the delivery tube, a cam disk mounted with its 100 axis above and parallel with the driving shaft, driving gear for rotating the cam disk, cams on one face of the disk situated about a path concentric to the axis of the disk, gearing for imparting to the helix a 105 cycle of motions successively consisting of forward rotation, backward rotation, period of rest, and means maintained in bearing 110 contact with the cams for controlling the operation of the gearing, for the purposes 115 set forth.

JAMES GEORGE JACKSON.
